(57) CLAIM

The ornamental design for a removable handle for cookware, as shown and described.

DESCRIPTION

FIG. 1 is an upper perspective view of the removable handle for cookware showing my new design.

FIG. 2 is a top plan view thereof;

FIG. 3 is a bottom plan view thereof;

FIG. 4 is a side view thereof;

FIG. 5 is an opposite side view thereof;

FIG. 6 is front elevation view thereof; and,

FIG. 7 is a rear elevation view thereof.

The features shown in broken lines form no part of the claimed design.
